UNITED STATES PATENT OFFICE.

GUSTAV A. BAEHR, OF BALTIMORE, MARYLAND, ASSIGNOR TO HERMINE BAEHR, OF BALTIMORE, MARYLAND.

DESIGN FOR A TOY RATTLER.

50,460.

Specification for Design.

Patented Mar. 20, 1917.

Application filed January 13, 1917. Serial No. 142,327. Term of patent 7 years.

To all whom it may concern:

Be it known that I, GUSTAV A. BAEHR, a subject of the King of Saxony, residing in the city of Baltimore, State of Maryland, have invented a new, original, and ornamental Design for Toy Rattlers, of which the following is a specification, reference being had to the accompanying drawing, forming part thereof.

Figure 1 is a front elevation of the toy illustrating my new design,

Fig. 2 is a side elevation of the toy, and Fig. 3 is a bottom plan view of the toy with the handle in sections.

I claim:

The ornamental design for a toy rattler, as shown.

GUSTAV A. BAEHR.
